(57) **CLAIM**

The ornamental design for a snow rail mounting bracket, as shown and described.

DESCRIPTION

Applicant's utility patent application Ser. No. 10/057,520, issued as U.S. Pat. No. 6,688,047, on Feb. 10, 2004, directed to a different embodiment of a snow rail mounting bracket, is related to the instant patent application.

FIG. 1 is a front elevational view of the snow rail mounting bracket showing my new design;

FIG. 2 is a right side elevational view thereof, the left side elevational view being a mirror image thereof;

FIG. 3 is a rear elevational view thereof;

FIG. 4 is a top plan view thereof;

FIG. 5 is a bottom plan view thereof; and,

FIG. 6 is an upper, right, front perspective view thereof.
